J. A. MIERZWIK.

HARROW.

APPLICATION FILED JUNE 23, 1917.

1,249,450.

Patented Dec. 11, 1917.

UNITED STATES PATENT OFFICE.

JOHN A. MIERZWIK, OF ROSCOE, TEXAS.

HARROW.

1,249,450.

Specification of Letters Patent. Patented Dec. 11, 1917.

Application filed June 23, 1917. Serial No. 176,592.

To all whom it may concern:

Be it known that JOHN A. MIERZWIK, a citizen of the United States, residing at Roscoe, in the county of Nolan and State of Texas, has invented certain new and useful Improvements in Harrows, of which the following is a specification, reference being had to the accompanying drawings.

This invention relates to certain improvements in harrows and it is an object of the invention to provide a device of this general character having novel and improved means whereby the slant of the teeth may be varied or changed in accordance with the requirements of practice.

It is also an object of the invention to provide a novel and improved harrow of a V-type together with means whereby the same may be readily expanded when required.

The invention consists in the details of construction and in the combination and arrangement of the several parts of my improved harrow wherein certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood I will now proceed to describe the same with reference to the accompanying drawings, wherein:

Fig. 1 is a view in top plan with portions broken away of a harrow constructed in accordance with an embodiment of my invention;

Fig. 2 is a longitudinal vertical sectional view taken through the device as disclosed in Fig. 1 with the central beam in elevation;

Fig. 3 is a sectional view taken substantially on the line 3—3 of Fig. 1; and

Fig. 4 is a sectional view taken substantially on the line 4—4 of Fig. 1.

As disclosed in the accompanying drawings 1 denotes a central tubular beam of predetermined dimensions and which has secured to the forward end portion thereof the upstanding member 2 to which suitable hitching means are adapted to be engaged or whereby the device may be operatively connected with a cultivator. The lower end

portion of the member 2 is horizontally disposed as indicated at 3 and is telescopically engaged with the forward end portion of the beam 1. Suitably secured to the horizontal portion 3 in advance of the beam 1 is the cross member 4 extending beyond opposite sides of the beam 1. Pivots engaged as at 5 with each of the opposite end portions of the member 4 is a side beam 6 also preferably tubular in form. The rear end portion of each of the side beams 6 has pivotally engaged therewith from below an arm 7 the inner end of which is pivotally engaged as at 8 with the members 9 slidably engaged with the beam 1 whereby it will be perceived that upon imparting requisite movement to the members 9 longitudinally of the beam 1 the side beam 6 will be either expanded or retracted relative to the beam 1. As here embodied the upper member 9 is provided with an upstanding arm 10 with which is pivotally engaged a rearwardly directed arm 11 having its rear end portion pivotally engaged with an upstanding operating lever 12 pivotally supported by the rear end portion of the beam 1. The lever 12 is of a conventional construction and is of substantially the same construction as the lever 14 to be hereinafter referred to. Suitably clamped to the forward end portion of the beam 1 is an upstanding member 16 having its upper portion provided with a barrel 17 through which is loosely directed the rod 18 disposed longitudinally of the beam 1 and having its inner end portion pivotally engaged with the transverse strap 19 carried by the lever 14 hereinbefore referred to. The forward portion of the rod 18 is operatively engaged with the intermediate or base portion of the substantially U-shaped member or yoke 20. The arms of the yoke 20 are forwardly directed and have their free end portions pivotally engaged as at 21 with the inwardly inclined end portions 22 of the bars 23.

Disposed transversely of each of the side beams 6 is a plurality of longitudinally spaced sleeves 24. Disposed through each of the sleeves 24 is a shank 25 having the outer end portion provided with a perforate head 26 while the opposite end portion of said shank has engaged therewith a clamping nut 27. The shank 25 in advance of the head 26 is provided with an upstanding arm

28 terminating in an inwardly directed lug
29 loosely disposed through an adjacent bar
23. Inserted through the lug 29 inwardly
5 of the bar 23 is a cotter pin 30 or the like
whereby the bar 23 is maintained in opera-
tive relation relative to the lug 29. Directed
through the perforate head 26 of each of the
shanks 25 is a harrow tooth 31. The slant-
ing of the teeth 31 is of especial advantage in
10 foul land as the teeth 31 can be disposed on
such an angle as to prevent balling espe-
cially in a field having corn or cotton stalks.

Pivottally supported at opposite sides of
the beam 1 adjacent the rear end thereof are
15 the harrow teeth 32 which extend above the
beam 1. The upper end portions of the
teeth 32 have pivotally engaged therewith
the link or yoke 33 which is also pivotally
engaged with the rearwardly directed end
20 portion of the strap 19 whereby it will be at
once self evident that the teeth 32 will be
moved in unison with and in the same gen-
eral direction as the teeth 31.

As before stated the member 2 provides
25 a means for securing my improved harrow
to a cultivator or affords a suitable hitch.
When the device is in use independently of
the cultivator the handles H are employed.
As herein disclosed the inner end portions
30 of the handles H are secured to the upstand-
ing member 16 through the medium of a
removable bolt 33 or the like. Interposed
between the outer end portion of the handles
H and the rear end portion of the beam 1
35 are the brace members 34. The lower or
inner end portions of the brace members 34
are operatively engaged with the pivot bolt
35 of the teeth 32 and which bolt 35 is
readily removable. It will be at once self
40 evident that with the use of the removable
bolts 33 and 35 the handles H together with
the brace members 34 can be readily re-
moved when it is desired to attach my im-
proved harrow directly to a cultivator.
45 Each of the levers 12 and 14 is provided
with a conventional latch mechanism 36 co-
acting with a rack 37 suitably secured to the
rear end portion of the beam 1.

From the foregoing description, it is
50 thought to be obvious that a harrow con-
structed in accordance with my invention is
particularly well adapted for use by reason
of the convenience and facility with which
it may be assembled and operated and it will
55 also be obvious that my invention is suscep-
tible of some change and modification with-
out materially departing from the appear-
ance and spirit thereof and for this reason I
do not wish to be understood as limiting my-
60 self to the precise arrangement and forma-
tion of the several parts herein shown in

carrying out my invention in practice except
as hereinafter claimed.

I claim:

1. A harrow comprising a central beam, a 65 cross member secured to the forward end
portion thereof, a side beam pivotally en-
gaged with each end portion of the cross
member, a plurality of shanks disposed
transversely of each of the side beams and 70
capable of rotary movement, upstanding
rock arms carried by the shanks, a bar oper-
atively engaged with each of said rock arms,
teeth depending from the shanks, and means
co-acting with said bar for imparting rock- 75
ing movement to the shanks.

2. A harrow comprising a central beam, a
cross member secured to the forward end
portion thereof, a side beam pivotally en- 80
gaged with each end portion of the cross
member, a plurality of shanks disposed
transversely of each of the side beams and
capable of rotary movement, upstanding
rock arms carried by the shanks, a bar oper-
atively engaged with each of said rock arms, 85
teeth depending from the shanks, a member
pivotally engaged with the forward end
portion of the bar, and means co-acting with
said last named member for imparting end-
wise movement to the bar for rocking the 90
shanks.

3. In combination with the side beams
of a harrow, shanks rotatably supported
by said beams, teeth depending from the
shanks, rock arms carried by the shanks, 95
bars operatively engaged with the rock arms
of the shanks, the forward end portions of
the arms being inwardly directed, a member
pivotally engaged with the inwardly directed
portions of the bars, and means co-acting 100
with said last named member for imparting
endwise movement to the bars.

4. A harrow comprising a central beam, a
cross member carried by the forward end
thereof, side beams pivotally engaged with 105
the opposite end portions of the cross mem-
ber, teeth depending from said side beams, a
member slidably engaged with the central
beam, arms pivotally engaged with the slid-
ing member and with the side beams, means 110
for imparting movement to the sliding mem-
ber longitudinally of the central beam for
expanding or retracting the side beams; said
teeth being capable of rocking movement,
and means carried by the central beam for 115
imparting rocking movement to the teeth.

In testimony whereof I hereunto affix my
signature in the presence of two witnesses.

JOHN A. MIERZWIK.

Witnesses:

T. M. DOBBINS,

JULIUS JOBB.
